DEVICE FOR INSERTING PACKING DISKS
IN BOTTLE CLOSURES

Heinrich Adam, Worms-on-the-Rhine, Germany,
assignor to Enzinger-Union-Werke Aktiengesellschaft, Pfeddersheim, near Worms, Germany, a corporation of Germany

Application May 11, 1933, Serial No. 670,494
In Germany March 17, 1933

6 Claims. (Cl. 123—30)

The invention relates to a device for automatically inserting packing disks in the closing caps in machines for closing bottles and the like vessels in which the closures are for example stamped out, pressed into form, provided with a cork or the like inset and set upon the bottles in a single working process.

If in such a machine the magazine for the packing disks which have to be inserted in the formed caps, is not kept supplied, the caps will be supplied to and set in the bottles without packing disks. It may further occur that incomplete disks, for example half disks are inserted in the caps. In such cases a gas-tight closure of the bottles is not obtained.

The object of the invention is to stop the machine automatically if either the magazine for the packing disks is empty or if damaged disks are supplied to the caps. In this way the provision of the bottles with closures which are not gas tight is avoided, which hitherto could not be noticed at all or only with difficulty and then usually too late.

According to the invention the packing disk is put under load by a slide which is sprung so that it adapts itself to the disk. The spring load is made such that only a complete undamaged disk can withstand it without buckling. If the spring load is not withstood through incompleteness or absence of the disk, the machine is automatically stopped and this will occur irrespective of the position of the damage.

The invention has the further advantageous feature that the stopping is effected by an extremely compact and simple means; levers, rods, and the like which particularly at high speeds interfere with sensitive action through inertia effects, are not employed.

An example embodying the invention is diagrammatically illustrated in the accompanying drawings.

Figure 1 is a plan view.

Figure 2 is a section on the line II—II of Figure 1 with a cork disk in position.

Figure 3 is a similar section, but with a cork disk absent.

Figure 4 is a partial cross section taken on the plane indicated by the line IV—IV in Figures 1 and 2, certain parts being omitted for the sake of clearness.

In Figure 1 it can be seen that the completely pressed cap 1 is carried by an intermittently rotating transferring disk 2 before being set upon the vessel to be closed, to an intermediate position 3 at which the packing disk is to be inserted.

This position of the cap is maintained by an arm 4 which is connected to a lever 5 through a pin 6, one end of the lever 5 being pulled by a spring 7 so that the other carrying a roller 8 coacts with an actuating cam 9.

In Figure 2, 10 is the magazine for the packing disks 11 which are piled therein. Beneath the magazine is a reciprocating slide 12 which at each reciprocation receives a disk from the magazine and carries it beneath a cap.

The slide 12 is movably mounted in a sliding block 13; it is thrust forward by a compression spring 14 and the relative movement limited by an abutment screw 15. The block 13 is guided upon a rail 16. The reciprocating motion of the block 13 is effected through a rod 17 actuated by a cam 18 through an angle lever 19. The stroke of the block 13 is greater than the movement required by the slide 12 to carry a packing disk from the magazine to the position in which it can be pressed into a cap. The slide 12 is therefore held back if an undamaged disk is present by the disk itself which abuts against the stop 20 and the spring 14 is compressed by the further part of the stroke of the block 13.

Figure 2 shows the position taken by the slide 12 when a packing disk of normal form has been brought beneath the cap. In this position the spring 14 of the slide 12 has been compressed. The insertion of the packing disk is now effected by an angle lever 22 actuated by a cam 21 giving a block 23 a rising and falling movement. The block 23 is guided by a pin 24 sliding in a hole in a boss 25. The block 23 carries a plunger 27 under the action of a spring 26. An abutment 31 receives the pressure.

Figure 3 shows the position if no packing disk is present. In this case the slide 12 makes the same stroke as the block 13 and the spring 14 is not additionally compressed. The slide 12 has been thrust so far forward that it partly enters the path of the plunger 27. Accordingly the upward movement of the plunger 27 ceases while the block 23 and the guide rod 24 continue their movement, the spring 26 being compressed. This continued movement of the block 23, through a cam slot 28 carried by the plunger 27 moves a bolt 29 guided in the block 23 in the direction of the arrow. The bolt accordingly engages a safety lever 30 by which the machine is stopped in any convenient manner. The same action takes place if an incomplete disk or any part of a disk is supplied to the slide 12, as the spring 14 then overcomes the resistance, if any, of the disk.

What I claim is:

1. In a device for transferring packing disks from a magazine to a point where they are inserted in caps for closing bottles and the like vessels, the combination of a reciprocating slide for transferring a disk from a magazine to a point where said disk is inserted into a cap, a stop against which said disk abuts when it reaches said point, intermittently rotating means for feeding caps in succession to said point, means for holding a cap in position while at said point, a reciprocating block having a longer stroke than required by said slide, yieldable spring means connecting said slide and said block, and means stopping the device when said spring means are not resisted by the abutment of a complete disk against said stop. 5
2. In a device for transferring packing disks from a magazine to a point where they are inserted in caps for closing bottles and the like vessels, the combination of a reciprocating slide for transferring a disk from a magazine to a point where said disk is inserted into a cap, a reciprocating block having a longer stroke than required by said slide, yieldable spring means connecting said slide and said block so that they move together until nearly the end of their stroke, an abutment stopping a disk when it reaches the position for insertion, and means for stopping the device actuated when no relative movement takes place between said slide and said block, said spring being strong enough to prevent such relative movement except when a complete disk comes against said abutment. 10
3. In a device for transferring packing disks from a magazine to a point where they are inserted in caps for closing bottles and the like vessels, the combination of a reciprocating slide for transferring a disk from a magazine to a point where said disk is inserted into a cap, a stop against which said disk abuts when it reaches said point, a reciprocating block having a longer stroke than required by said slide, yieldable spring means connecting said slide and said block, a reciprocating resilient plunger for transferring a disk from said slide into a cap, said slide moving into the path of said plunger, at the end of its stroke when said spring means are not resisted by the abutment of a complete disk against said stop, and means for stopping the device when said plunger strikes said slide. 15
4. In a device for transferring packing disks from a magazine to a point where they are inserted in caps for closing bottles and the like vessels, the combination of a reciprocating slide for transferring a disk from a magazine to a point where said disk is inserted into a cap, a stop against which said disk abuts when it reaches said point, intermittently rotating means for feeding caps in succession to said point, means for holding a cap in position while at said point, a reciprocating block having a longer stroke than required by said slide, yieldable spring means connecting said slide and said block, and means stopping the device when said spring means are not resisted by the abutment of a complete disk against said stop. 20
5. In a device for transferring packing disks from a magazine to a point where they are inserted in caps for closing bottles and the like vessels, the combination of a reciprocating slide for transferring a disk from a magazine to a point where said disk is inserted in a cap, an abutment stopping a disk in position at said point and through said disk stopping said slide, a reciprocating block having a longer stroke than required by said slide, a bolt forming a lost motion connection between said slide and said block, a compression spring normally taking up said lost motion and yielding when a complete disk stops said slide, and means for stopping the device when said spring does not yield through absence of a complete disk. 25
6. In a device for transferring packing disks from a magazine to a point where they are inserted in caps for closing bottles and the like vessels, the combination of a reciprocating slide for transferring a disk from a magazine to a point where said disk is inserted into a cap, a stop against which said disk abuts when it reaches said point, a reciprocating block having a longer stroke than required by said slide, yieldable spring means connecting said slide and said block, a second reciprocating block, a resilient plunger on said second block for transferring a disk from said slide into a cap, said slide moving into the path of said plunger, at the end of its stroke when said spring means are not resisted by the abutment of a complete disk against said stop, and means for stopping the device when said second block moves relatively to said plunger. 30
